UNITED STATES PATENT OFFICE.

IRVING B. SMITH, OF PHILADELPHIA, PENNSYLVANIA, ASSIGNOR TO ELECTRELLE COMPANY, OF PHILADELPHIA, PENNSYLVANIA, A CORPORATION OF PENNSYLVANIA.

AUTOMATIC MUSICAL-INSTRUMENT PLAYER.

1,109,554.

Specification of Letters Patent. Patented Sept. 1, 1914.

Application filed March 23, 1908. Serial No. 422,768.

To all whom it may concern:

Be it known that I, IRVING BELL SMITH, a citizen of the United States, residing at Philadelphia, in the county of Philadelphia and State of Pennsylvania, have invented new and useful Improvements in Automatic Musical-Instrument Players, of which the following is a specification.

My present invention relates to automatic musical instrument players of that type wherein the sound producing devices of the musical instrument, (such for instance as the hammers of a piano) are operated by electro-magnetically controlled actuating devices influenced by, and responsive to, the note perforations in a perforated music sheet.

The present improvements have been designed primarily as an "attachment" to be applied to the known makes of upright pianos without in any way altering the usual construction of such instruments and without interfering with free manual or hand-playing thereof; although I do not wish to be understood as limiting myself specifically to what might in a limited way be termed an "attachment", as it will be obvious that the playing mechanism herein shown and described may be so associated with and installed in a piano during the manufacture of the latter as to constitute and form a part thereof, as distinguished from what might otherwise be termed or classed as an attachment.

Experience resulting from a long series of costly experiments has demonstrated that many advantages and much better results are secured by placing the playing mechanism or actuating elements for the sound producing devices, *i. e.*, the hammers, in the upper part of the piano case, but owing to the narrow and limited extent of the unoccupied space in this part of the piano, it has been difficult to provide an entirely satisfactory construction of playing mechanism having the requisite strength, compactness, and simplicity, that can be attached within all existing makes of piano cases without, in some instances at least, requiring either a cutting of the case or a reconstruction of some of the parts of the playing mechanism.

One of the prime objects therefore of the present invention is to provide a strong, compact, simple and efficient construction of

electro-magnetically controlled playing mechanism that may be easily and quickly attached to any of the ordinary makes of pianos, the several elements of the mechanism being so constructed and arranged that no muffling of the musical tones will result from its use and ample free space will be left, when the mechanism is in position for use, to enable the piano to be readily tuned without removing or shifting the position of said mechanism, which is a desideratum of considerable importance.

A further object of the invention is to provide a novel and simple construction of "carrier" or supporting rail for the playing mechanism. In this construction, the series of electro-magnets employed to influence the operation of the piano hammers are of the "iron-clad" type and disposed side by side and united in such manner that the shells thereof themselves constitute the supporting rail. The adoption of this type of magnet-rail, and the associated arrangement of parts, not only produces a very compact, rigid structure but also renders possible the use of primary batteries for furnishing the necessary controlling current, a result hitherto impractical, on account of the large amount of current required by existing makes of playing mechanism.

A still further object of the invention is to provide improved manually operable means under the control of the performer for moving all, or a series, of the piano hammers in the treble, middle or bass, toward and from the piano strings in order to secure a great variety of variations in musical expression according to the musical score, or the individual concept of the performer, said means operating to effect a regular gradation of the tones.

A still further object of the invention is to provide improved means for automatically taking up the slack in the flexible connections between the actuating elements of the player mechanism and the hammer actions whereby to maintain said connections operatively taut at all times, said means being co-operatively associated with and operable through the same instrumentalities employed to actuate the expression means.

The invention has in view other more or less important objects as will hereinafter

appear in the following detailed description of the various parts illustrated in the accompanying drawings, wherein:-

Figure 1 is a transverse vertical section 5 through an ordinary piano showing my improved playing mechanism in position therein, the section being taken substantially on the line 1—1 of Fig. 3. Fig. 2 is a plan view of the playing mechanism complete. 10 Fig. 3 is a front elevation of the playing mechanism, also showing parts of the expression mechanism. Fig. 4 is a fragmentary perspective showing my novel construction of magnet rail. Fig. 5 is a perspective 15 view on an enlarged scale, showing an armature, and shoe attached thereto. Fig. 5^a is a sectional view through the shoe, showing the method of attaching the hammer actuating tape thereto. Fig. 6 is a sectional view 20 on an enlarged scale substantially on the line 6—6 of Fig. 3, looking in the direction of the arrow, and showing details of the expression mechanism, and slack adjusting means. Fig. 7 is a similar view taken 25 substantially on the line 7—7 of Fig. 3 looking in the direction of the arrow. Fig. 8 is a plan view of the mechanism shown in Fig. 6. Fig. 9 is a transverse section through my improved magnet rail and associated 30 parts. Fig. 10 is a perspective view on an enlarged scale of a fragment of the magnet rail showing an armature and the adjustable spring therefor. Fig. 11 is a similar view, 35 looking at the other side of the magnet rail, and showing the means for attaching the armature thereto. Fig. 12 is a fragmentary view, similar to Fig. 9, showing a slightly modified construction of magnet rail. Fig. 40 13 is a plan view of the controlling levers for the expression mechanism and associated parts. Fig. 14 is a side elevation of the same. Fig. 15 is a detail perspective of the end of one of the controlling levers. Fig. 45 16 is a transverse section on an enlarged scale through the supporting bracket, substantially on the line 16—16 of Fig. 1. Fig. 17 is a diagrammatic view, conventionally illustrating the music-roll holder, and reader mechanism, and showing the electric 50 circuits employed. Fig. 18 is a side elevation of a modified form of supporting bracket, showing the magnet rail in position. Fig. 19 is a front elevation thereof, the magnet rail being omitted for the sake 55 of clearness. Fig. 20 is a detail perspective view similar to Fig. 10, but showing a modified construction. Fig. 21 is a perspective view similar to Fig. 11 but further illustrating the construction shown in Fig. 20. 60 Fig. 22 is a transverse section through the magnet rail illustrated in Fig. 20. Figs. 23 and 24 are views of the expression mechanism similar to Figs. 6 and 7, respectively, and showing a slightly modified construction. 65

It will be understood that the player mechanism forming the subject matter of the present invention is designed to be controlled in its operation through the medium of perforated music sheets which travel 70 from a delivery roll or spool over a suitable tracker or reader onto a take-up roll as is usual in instruments of this class, the said delivery, take-up rolls and tracker or reader being usually carried by what is known as a "music roll holder", but as such "holder" forms no part of the present invention it will not be shown or described in detail, although the essential parts thereof necessary to a full and complete understanding of the present invention, will, later on in this specification, be shown and described in a conventional way.

Referring to the drawings in detail 1 indicates the frame or bolster of any well known make of piano and 2 designates the case thereof. The key-board is designated by 3, and 4 indicates the usual keys.

5 is the string plate on which are stretched the strings 6 in the well known manner. 90 The usual hammers 7, supported by shanks 8, are pivoted at 9 to the hammer rail 11, and connected with the wippen 10 of the hammer action.

The playing mechanism complete is supported in the upper part of the piano case by means of brackets 12 bolted to the string plate or frame of the piano. As clearly shown in Figs. 1, 2, and 16, a plate 13 is provided with an overhanging lip 14 which embraces one edge of the depending bracket 12, and is secured by means of bolts 17 to the magnet rail 21, hereinafter described. A bolt 16 passes through an elongated slot 15 in the bracket 12, and is secured to the plate 13. Another plate 18 is interposed between the plate 13 and the magnet rail, and a third plate 19 is interposed between the edge of the plate 18 and bracket 12, and is secured in position by means of a bolt 20 passing through the plate 13. It will thus be seen that by the construction above described, a readily adjustable attaching and supporting means is provided, which lends itself to all practical requirements.

21 designates my improved magnet rail in its entirety. As clearly shown in Fig. 4, this rail consists of a bar of magnetic material, preferably of rectangular cross section, and in which is formed a series of vertically extending transverse chambers 22. As shown in Fig. 9, I insert a magnet core 23, preferably of soft iron, in each of these chambers, and provide the core with an enlarged bottom which may be screw threaded or otherwise secured in position in the chamber. If preferred however, and as shown in Fig. 12, I may form the bottom of the chamber integral with the rail 21^a, and provide an opening merely large enough to ac- 125 130 135 140 145 150 155 160 165 170 175 180 185 190 195 200

commodate the end 23^a of the core. An annular space or pocket above this bottom is thus provided between the core and the walls of the chamber, and in this space is disposed 5 a magnet coil 24. It will thus be seen that the above described arrangement produces a series of magnets of the "iron-clad" type, the outer shells of which are integrally united so as to form the supporting rail. As 10 is well known, magnets of this type possess a much higher efficiency than magnets of other types, and are capable of producing a stronger pull with a smaller energizing current. Moreover this construction of magnet 15 rail results in the production of a very compact and comparatively narrow mechanism, which is of such size that it can readily be inserted in all existing makes of upright pianos without in any way changing or mutilating the same.

One set of leads 27, from the magnet coils 24 extend through openings 25, provided with insulated bushings 26, and are soldered or otherwise secured to a common conducting bar 28, secured to the side of the magnet rail by means of screws 29, but insulated therefrom. The other set of leads 32, from the coils 24, extend through openings 30 near the top of the magnet rail, provided 30 with insulating bushings 31. Each of these leads 32 is soldered or otherwise secured to a metal clip 33, which is mounted on a bar 34 of insulating material secured to the side of the magnet rail. From binding screws 35 37, carried by each clip 33, extend insulated wires 35, which wires are bound into a suitable insulated cable 36, which is strung along the side of the magnet rail in any suitable position.

40 Clamped between the insulating bar 34 and the magnet rail 21 is a spring strip, preferably formed of sheet steel, and provided with a number of upstanding teeth 40, one corresponding with each chamber or 45 pocket in the magnet rail. Openings 39 are formed through this strip to accommodate the leads 32 above described, which leads lie in grooves 38 formed in the upper surface of the bar 34.

50 41 designates my improved form of armature which is associated with each of the iron clad magnets above described. As clearly shown in Figs. 5, 10, and 11, the armature comprises a rigid body portion, 55 and a spring plate 42, secured to the body portion near one end, as by means of rivets, but spaced apart therefrom throughout substantially its entire length. The spring plate is bent downwardly over the end of the rigid 60 body portion of the armature, and is provided at its lower free end with projecting conical pintles 44 hereinafter referred to. Each armature is supported slightly above the surface of the magnet rail by means of 65 a screw 43, which is set into a bifurcated

tooth 40, of the spring strip and, after the armature has been properly adjusted, is tightened up so as to clamp the spring tooth between the head of the screw and the end of the armature. This affords a ready means of adjusting the armature to a nicety, and also affords a resilient and noiseless support for the same. A set screw 45 passes loosely through the spring plate 42 near its free end and serves to limit the movement of said plate relative to the body portion of the armature. A small groove 46 is formed in the lower face of each armature near its end for the purpose of accommodating a spring hereinafter described.

49 designates a friction shoe, provided, as is usual, with a facing 50, of cork or the like. To the upper end of said shoe is secured a clip 47 held in position by means of screws 48. This clip is formed with spaced resilient ears which, as clearly shown in Fig. 5, are adapted to be sprung over the depending free end of the armature plate 42 so as to embrace the same, and are provided with openings which engage the pintles 44, and thus constitute a pivot for the shoe. The clip 47 is provided near its other end with an opening 51, the metal from which, as clearly shown in Fig. 5^a, is folded back under the clip as at 52 and serves to bite into and firmly grip the end of the tape 53 which passes up through the opening 51 and is secured at its other end to the wippen or other suitable part of the hammer action.

It will of course be understood that, as clearly shown in Figs. 2 and 3, a magnet armature, shoe, and tape are provided for each key of the piano, but as these parts are duplicates of each other, and interchangeable, the description of one will suffice for all.

The tapes 53 are preferably passed around a fixed guide bar 54, carried by the piano action, and interposed between the friction shoes and hammer actions in such manner as to hold the tapes out of the path of movement of any of the parts of the mechanism.

To the side of the magnet bar underneath the free ends of the armatures 41 is attached a plate 55, provided with an outwardly turned notched edge 56. A spring 59, preferably formed of steel wire, has one end arranged to lie in the groove 46 of each armature and, after being wrapped once or more loosely around a stud screw 58 set into the side of the magnet rail, has its lower downwardly extending end 57 engaged by one of the notches 56 of the plate 55. It will therefore be evident that by setting the extension 57 in different notches, any desirable degree of tension may be given to the spring 59. Other means for adjustably holding the end of the spring may readily be devised without departing from the spirit of the invention.

These springs 59 normally urge the arma-

105

110

115

120

125

130

ture upwardly away from the face of the magnets, and stops are therefore provided to limit this upward movement of the armatures. These stops preferably comprise plates 60, secured at one end as at 61 to the magnet rail between the armatures, and having their other ends 63 overhanging the armatures. A set screw 62 passes loosely through each plate 60 and into the magnet rail, and serves, as will be apparent, to adjust the height of the free end 63 of the plate and therefore to vary the amount of movement which the armature may have. Pads, 64, of felt or similar material are preferably secured to the under sides of the plates 60 in order to render the operation of the armatures silent.

The springs 59 by their tendency to urge the armatures upwardly and away from the face of the magnets, also serve to lessen the shock or force of contact when the shoes are brought into frictional engagement with the actuating drum or power shaft.

The shoes 49 are co-operatively associated with a rotary drum 65, which is preferably of conical form, and is supported in brackets 74, secured to the magnet rail 21. It is journaled at each end in ball bearings as at 63^a, and at one end, is provided with a pulley 121, hereinafter referred to. It will be understood that the shoes are normally held away from the drum, and are forced into contact therewith whenever the corresponding magnet is energized.

In piano playing mechanisms of this type it is customary to provide a rest rail for the hammer heads, which rail is capable of being moved toward and away from the strings in such manner as to vary the stroke of the hammers, and hence vary the intensity or loudness of the sound produced. In the drawings this rest rail is designated by 66, and in order that the hammers may be moved to a different extent in the treble, middle and bass of the instrument, this rest rail 66 is made flexible as by hinging the same near its middle as at 67^a. The rest rail is pivoted at its ends 68 in the lower end of levers 69, and at its middle, the hinge is secured to the lower end 67 of a lever 70. The levers 69 are in turn pivoted near their middle to crank levers 72, which are carried at the outer end of longitudinally extending shafts 73 and 75. These shafts are journaled at their outer ends in the brackets 74.

By reference to Fig. 3 it will be seen that the shaft 75 extends to an intermediate bracket 77^a and that the shaft 73 extends from this bracket to the outer bracket 74. A third shaft 76 is journaled at one end in the bracket 77^a and at its other end in a second intermediate bracket 77, and carries at its end a crank lever 83, which is pivoted to the middle of lever 70. Secured to the shafts 73, 75, and 76, respectively, are

cranks 80, 81 and 82, arranged in proximity to each other, for the purpose hereinafter described. Each of the shafts 73, 75, and 76 has a spring coiled around one end thereof such spring being secured at one end to a collar 78 adjustably fixed to the shaft, and at the other end, being attached to one of the brackets 74 or 77.

The levers 69 at each end of the rest rail 66 are, as above stated, pivoted to the end of the cranks 72, and at their upper ends are provided with an open slot 89 which takes over a pin 90, supported by the bracket 74, and spaced therefrom by means of a bushing 91, as shown in Fig. 8. The upper end of the middle lever 70, supporting the rail 66, is also provided with an open slot 93 at its upper end which cooperates with a pin 95 carried by a bracket 94 secured to the magnet rail 21. This lever 70 is pivoted at its middle at 70^a, to the end of the crank 83 above referred to. The object of so supporting the levers 69 and 70 is to cause their lower ends, carrying the rest rail, to move in a path which approximates the arc of a circle of which the pivot point 9 of the hammers is the approximate center. In Figs. 6 and 7 the path of movement of the rest rail 66 is shown by the broken line 96. The full line position of the parts in these figures illustrates the condition of the mechanism when set so as to allow the hammers to have the longest possible stroke thus producing the loudest or fortissimo effect, while the dotted lines indicate the position of the parts when the rest rail is moved closer to the strings so as to produce a soft or pianissimo effect.

It is evident that were the levers 69 and 70 pivotally mounted at 90 and 95 respectively, their lower ends, and consequently the rest rail, would swing in the arc of a circle with these points as centers. The hammer heads, of course, move in the arc of a circle with the point 9 as a center, and since, these two arcs are reversely curved, it is obvious that if the rail should move from one position to the other, there would be a sliding of the hammer heads on the rest rail which would produce a very objectionable frictional resistance. By the use of the slots 89 and 93 however, arranged as above described, the rest rail and hammer heads are caused to move in substantially the same path, whereby all sliding and friction between the parts is eliminated.

The above described shifting of the position of the hammers toward and from the strings results in shifting, more or less, the parts of the hammer action to which the tapes 53 are attached. In order to compensate, therefore, for such movement of the parts, and to automatically take up any slack which may be created in the tapes, and to preserve a proper tension therein, I have

found it desirable to provide a shiftable slack-adjusting bar 84, clearly shown in Figs. 2, 3, 6, 7 and 8. This bar is, like the hammer-rest rail, hinged at its middle to the upper end 85 of the lever 70, and at its outer ends, it is carried in brackets 85, which in turn are pivoted as at 92 to the upper end of the levers 69. The brackets 85 are provided with transverse arc-shaped slots 86, working over screws 87, set into the upper end of levers 69, and spaced therefrom by means of washers 88. By loosening either of the screws 87 and moving the corresponding bracket up or down, it may be adjusted so as to vary the amount of movement imparted to the bar 84. In Figs. 6 and 7 the dotted line indicates the position occupied by the tapes 53, when the rest rail is moved to its pianissimo position.

The springs 79 normally cause the shafts about which they are wound to maintain the rest rail 66 in its advanced or pianissimo position, shown in dotted lines. In order, therefore, to move the rest rail back toward its full line or fortissimo position the following mechanism is provided: To the outer end of each of the crank levers 80, 81, 82 is attached one end of a tape 98 by means of a set screw 97. As clearly shown in Fig. 1 these tapes 98 extend downwardly through an opening in the key-board, and after being passed around cams 99, (see Fig. 14) are secured to the ends of the rock levers 100. These levers 100 are pivoted at 101 to a bracket 102, adapted to be secured to the under side of the key-board. Riveted to each of the levers 100 is a bell-crank lever 103, which carries at its end a socket 104, adapted to detachably receive the end of a removable key lever 106 which carries at its outer end a finger plate 105. The key lever 106 is provided with a saw-cut 107, to render the same resilient, and with a transverse slot 108 adapted to coöperate with a pin 109, carried by the socket 104, and which prevents the relative rotation of the parts. The parts 100, 103, 105, and 106, taken collectively, will be hereinafter referred to as "expression levers". A pawl 110 projects inwardly from each of the finger plates 105, and is adapted to coöperate with a row of openings 111, formed in a curved plate 112, through open slots in which the key levers 106 project. This curved plate 112 is pivoted near its upper end to a bracket 113, adapted to be secured to the key-board. Pivoted at 114 to the plate 112 is one end of a pair of links 115, the other ends of which are pivoted to a yoke 116, which in turn is pivoted to a shaft 118, carried in a bracket 119 secured to the bottom of the key-board. The yoke 116 carries three bolts 117, having at their ends leather cushions 117^a, adapted to come in contact with the faces of the cams 99. These cams 99 are mounted

on ball bearings 120, on the shaft 118 in such manner as to be capable of independent movement. It will now be apparent that by depressing any one of the finger plates 105 the corresponding expression lever is moved, 70 with the result that the respective tape 98 is drawn downwardly, and operates the corresponding rock shaft 73, 75, or 76, moving the rest rail 66 accordingly. By setting the end of the pawl 110 in any one of the series of openings 111, the parts may be maintained in any desired position to which they are moved. The cams 99 have a double function. In the manipulation of the key levers above described the cams are moved 75 individually and in accordance with the respective expression levers, and when so moved, they have the effect of causing the tapes 98 to move with progressively increasing rapidity as the levers 106 are depressed. 80 By this arrangement the regulation of expression is rendered more sensitive and delicate, since, during the first part of the movement of the levers 106, the shifting of the rest rail is comparatively small, while during 85 the last part of the stroke of said levers, the movement of the rest rail is proportionately much greater. This enables the desirable shading of expression to be much more readily produced than in the constructions 90 heretofore employed. 95

When it is desired to play the piano manually in the ordinary manner, the curved plate 112 is swung on its pivot inwardly and upwardly as indicated by the arrow in Fig. 14, to the position shown in dotted lines. The links 115, acting on the yoke 116, swing the same forward, and the yoke then throws all three of the cams into the position shown in Fig. 1, or in dotted lines in Fig. 105 14. This throws the rest rail 66 to its full line position, and maintains it in such position, while at the same time the plate 112 lies under the key-board practically out of sight. In this position of the parts, the key 110 levers 106 may be detached from the sockets 104 and removed.

In Fig. 17 I have diagrammatically illustrated the arrangement of parts in relation to the electrical circuits employed, and have 115 also conventionally illustrated a reader mechanism, and the associated delivery and take-up rolls for a perforated music sheet. 124 indicates any suitable form of electric motor provided with a pulley 122 which is connected by a belt 123 with a similar pulley 121 carried on the shaft of the rotary drum 65, above described. The leads for supplying current to this motor are indicated at 125, 126. Current enters at 125, and after 120 passing through the cut-out switch 127, the starting switch 128, and the motor 124, flows to the negative lead 126. The cut-out switch 127 is controlled by a magnet 129 one side of which is connected by wire 130 125 130

to a battery 131. From the other side of the magnet 129 extends a wire 132, to a contact device 136. From the battery 131 also extends a wire 134 to the common conductor bar 28, secured to the magnet rail. The leads 32 from the magnets, which in Figs. 9 and 11 are shown as formed into a cable, extend to the reader device. This consists essentially of a series of spring fingers 141, each connected to its respective lead 32, which spring fingers are associated with a contact bar 135, connected by a wire 133 to the other side of the battery. Coöperating with the spring fingers 141 and the contact bar 135, and serving to control the passage of current to the several magnets, is a perforated music sheet 138, which is wound on delivery and take up rolls 139, 140 respectively. Suitable means, (not shown) are provided for driving the take up roll 140 from the motor 124, or from the drum 65. It is therefore evident that as each note-perforation 142 passes under any contact finger 141, current will flow through the connected lead 32 and the corresponding magnet will be energized, and the corresponding hammer operated by means of the shoe 49 and tape 53.

In order to stop the motor automatically when the music sheet has been all unwound from the delivery roll, a special perforation 137 is provided in the sheet near its end, and when this perforation passes under the contact device 136 above described, current will flow from the battery 131 through the magnet 129 and open the cut-out switch 127, thus stopping the operation of the mechanism, and permitting the music sheet to be removed from the holder.

Instead of the construction of supporting bracket shown in Figs. 1, 2, 3 and 16; I may, and preferably do, employ the arrangement illustrated in Figs. 18 and 19. Referring to these figures, 202 indicates the modified form of bracket which is provided at one end with a shank 203 formed with lag screw-threads 204, adapted to be screwed in to the bolster 1 of the piano frame. At its lower end the bracket 202 is provided with a depending screw threaded portion 205. A clamp 210, having a tubular portion adapted to fit loosely over the screw-threaded shank 205, is secured in place thereon by means of nuts 206, 207 and 212. The clamp is provided with a dovetail groove 209, which is adapted to embrace a dovetail slide 208, secured to the magnet rail 21. Set screws 211 are carried by the clamp and are adapted to bear against the slide 208 and maintain the parts in any position in which they may be set. It will be evident that this construction of supporting bracket provides for universal adjustment. By screwing the shank 203 more or less into the bolster 1, the distance between the

player mechanism and the string plate may be determined. By moving the clamp up or down on the shank 5 and securing it in position by means of the nuts 206 and 207, and lock nut 212, it will be seen that any desired vertical adjustment of the player mechanism relative to the hammer actions may be secured, and, by loosening the set screws 211 and sliding rail 21 through the clamps 210, it will be seen that the position of the player mechanism may be adjusted longitudinally of the hammer actions.

Instead of the construction illustrated in Figs. 9, 10 and 11 I may, and preferably do, employ the arrangement shown in Figs. 20, 21 and 22. Referring to these figures, reference numeral 21 designates the magnet-rail while 41 and 42 indicate the armature and associated spring plate, respectively. 45 designates the set screw for adjusting these parts relative to each other. In this construction, however, the upstanding teeth 216 of the spring strip are not bifurcated as in the former arrangement, but are provided with elongated slots 226 through which the screws 226^a pass. These slots provide means for the vertical adjustment of the armatures. Supported above the magnet rail 21 and spaced apart therefrom by means of bushings 225, is a stop rail 218 secured in position by means of screws 224. Into one edge of this stop rail is set a series of stud screws 217, the head of each of which is adapted to abut against the corresponding end of one of the teeth 216. A check spring 219 surrounds each of the screws 217. It will be apparent therefore that, by manipulating any screw 217, the tension of the corresponding spring tooth 216 may be adjusted as desired, and consequently its retractive effect on its armature correspondingly varied. In place of the overhanging plates 60, shown in Fig. 10 I employ a series of stop screws 220 set into the stop rail above each armature, and provided at their lower ends with suitable pads of felt, suitable check-springs 221 being interposed between the heads of the screws and the stop rail. These screws may be manipulated from above, and it is evident that by properly adjusting them the movement of the armatures away from the magnet rail may be limited to any extent desired.

Heretofore, in piano-player mechanisms employing a series of electro-magnets, it has been found necessary, in order to prevent the disagreeable clicking of the armatures against the pole pieces, to cover one of said parts with a layer of silk tape or similar sound-deadening material. This, however, has had the objectionable effect of very greatly weakening the power of the magnets. In order to obviate the necessity for interposing any such cushioning material, and to limit the movement of the armatures

toward the magnets, I provide a series of 5 spring plates 222. As clearly shown in Figs. 20 and 22, these plates are secured at one end to the magnet rail, as at 230, and near the other end are provided with a perforation 10 through which projects the head 229 of a shouldered stud-screw set into the magnet rail. The free end 222 of each of these spring plates is bent downward and extended 15 to one side, so as to project underneath the adjacent armature, and is provided with a pad 223 of felt, or similar material, against which the armature may strike. It will be seen, therefore, that by 20 properly adjusting the screw 229 the end of plate 222 may be raised or lowered and the movement of the armature toward the magnet poles may be stopped at any desired point, and it has been found that by this 25 arrangement, it is possible to secure silent operation of the parts and at the same time to very much increase the efficiency of the magnets. In other words, the stop pad 223 may be so adjusted that the armature can 30 approach the pole pieces much nearer than the thickness of the silk tape heretofore employed, would permit.

While I have shown and described my invention as applied to playing mechanism of 35 the shoe and roller type, it will be understood, of course, that I do not wish to limit myself in this respect, as there are many features of my invention which are equally applicable to other types of playing mechanism, such, for example, as those in which 40 the hammers are actuated by direct magnetic pull. I desire to state therefore, that where, in the annexed claims, I use the expression "hammer actuating elements" I intend it to 45 cover not only friction shoes, but also, all other devices, such as push rods, and the like, which may be employed in any type of playing mechanism, and which constitute an operative connection between the armatures and hammer actions.

In some types of pianos it is necessary to 50 provide means for taking up the lost motion in the hammer action resulting from the movement of the rest rail toward its "pianissimo" position. To accomplish such result, I provide the mechanism illustrated in 55 Figs. 23 and 24, and which mechanism may be employed in connection with the expression mechanism described in this application. In these figures, which are views corresponding to Figs. 6 and 7, respectively, the 60 same reference characters have been employed to indicate the parts which are duplicates of those shown in the preceding figures, and other characters have been used to designate the additional features.

The levers 72 and 83 of the other figures 65 are slightly modified in this arrangement and are designated 172 and 183. The levers 172 have elongated slots 172^a formed therein,

and in these slots are set clamp screws 173. The brackets 174 have extensions 175 carrying at their ends rollers 176. Secured at one end to the clamp screws 173, and passing downwardly over the rollers 176 are a pair 70 of cords 179, arranged one at each end of the piano.

Lever 183 which is disposed near the middle of the piano, is provided with an elongated slot 184 in which is set a clamp-screw 75 185. The bracket 177, supporting these bars, is provided with an extension carrying at its end a guide roller 178. Secured at one end to the clamp screw 185 and extending downwardly over the roller 178 is a cord 80 186. These cords 179 and 186, disposed one at each end, and one in the middle of the piano, respectively, extend downwardly to the mechanism now to be described.

The hammer butts are shown at 146, and the jacks at 147. These jacks are pivotally connected with the wippens, which are shown at 148. Pivotally connected with each wippen is a centrally disposed lever 149. Disposed underneath the ends of the 85 levers 149 is a cross-bar 150, which is secured to the lower ends of the cords 179 and 186. Secured to this cross-bar are links 150^a, 150^b which are pivotally connected with a fixed support 160. The cross-bar 150, like the 90 hammer rail rest, is hinged in the middle. By this arrangement the cross-bar is adapted for executing a slight arcuate movement, in response to vertical movements of the cords 179 and 186. Secured to the ends of 100 the cross-bar, and to its middle, are clips 151 and 152, respectively. From clips 151 extend rods 153, which are provided at their upper ends with heads 155, which rest in 105 hangers 157, carried by the rest rail 66. A similar rod 154 extends upwardly from the clip 152, and is provided at its upper end with a head 156 which rests in a hanger 158. This hanger is secured, as by a nut 159, to the lower end of the lever 70, 110 on which the rest rail 66 is hinged at its middle.

The cords 179 and 186 are attached at 115 their lower ends to the cross bar 150, as clearly shown in the drawings. It will therefore be seen that, as the levers 172 and 183 are rocked, so as to move the rest rail 66 toward its "pianissimo" position, the cords 179 and 186 are drawn upwardly, thus lifting the cross-bar 150 and raising the wippens 148 by means of the arms 149, and thus taking up the lost motion which would otherwise result between the hammer butts 146, and the jacks 147. The slots 172^a and 184 permit of adjustment of the clamping 120 screws 173, 185, so that the amount of take-up of the cords 179 and 186, may be varied, as desired.

In certain well-known makes of pianos, it 125 has heretofore been common to take up lost 130

motion in the hammer action by means of a rigid cross-bar corresponding to 150, supported by rods from the hammer rest rail, but, owing to the peculiar movement of the rest rail in the present invention I have 5 found it necessary to provide the above described means in addition to, and separate from, the rest rail for taking up this lost motion, as the rest rail is moved.

10 By virtue of the special construction of magnet rail which I have shown and described, I am enabled to employ ordinary dry batteries for operating the controlling magnets. This is due to the fact that, as 15 above pointed out, magnets of the iron-clad type have a higher efficiency than magnets of any other kind, and require a much smaller magnetizing current. It will also be observed by reference to Fig. 9 that the 20 armature lies across the face of the magnet rail in such a manner as to form with the core 23 and walls of the pocket, a closed magnetic circuit of small reluctance. Heretofore a great objection to the use of electrically-controlled piano-players has been 25 the necessity for using a rotary converter or similar device, for the purpose of transforming ordinary street or lighting current into current of a voltage suitable for operating 30 the controlling magnets. The voltage of the ordinary street current is too high, since it produces destructive sparking at the contact-fingers, and heretofore it has been impractical to employ primary batteries, for 35 the reason that the consumption of current and consequent cost of maintenance was prohibitive.

In the present design I have produced a construction by which the use of the objectionable converter has been eliminated, and 40 in which the cheap and well known dry batteries may be readily and effectively employed. While I have shown an electric motor for operating the drum it will be 45 understood that I do not of course limit myself in this respect, since it is obvious that any desired form of motor device may be employed as circumstances may dictate. For example, in localities where street current 50 is not available, I may employ foot power mechanism for driving the drum and take up rolls.

It will thus be seen that I have provided 55 a piano-playing mechanism which obviates a large number of the objections and difficulties heretofore experienced with such devices, and one which lends itself to a great variety of conditions, and it is thought that the numerous advantages of my invention 60 will be readily appreciated by those skilled in the art.

What I claim is:

1. In an electrically controlled playing mechanism for pianos, a series of magnets, 65 and a series of armatures associated there-

with, each of said armatures comprising a rigid body portion, and a superposed spring-plate secured thereto but spaced therefrom, and hammer actuating elements connected with said spring plates.

2. In an electrically controlled playing mechanism for pianos, a series of magnets, and a series of armatures associated therewith, each of said armatures comprising a rigid body portion and a superposed spring plate secured thereto at one end only and spaced therefrom but co-extensive therewith, and a hammer actuating element connected with the free end of each of said spring plates.

3. In an electrically controlled playing mechanism for pianos, a series of magnets, and a series of armatures associated therewith, each of said armatures comprising a rigid body portion movably supported at 85 one end, and a superposed spring plate, connected therewith near one end adjacent the support, and spaced apart therefrom substantially throughout its length, a set screw passing loosely through said spring plate 90 near its free end to limit its movement relative to the body portion, and a hammer actuating element pivoted to the free end of each of said spring plates.

4. In an electrically controlled playing mechanism for pianos, a series of magnets, and a series of armatures associated therewith, said armatures comprising rigid and resilient portions, shoes connected with the hammer actions and pivoted to the resilient 100 portions of said armatures, and a rotary drum arranged in co-operative relation with said shoes.

5. In an electrically controlled playing mechanism for pianos, a magnet rail, a series of armatures pivotally supported thereon, each of said armatures comprising a rigid body and a superposed spring plate, hammer actuating elements pivoted to said spring plates, adjustable means for limiting 110 the movement of each of said spring plates relative to the associated rigid body portion, and other adjustable means for limiting the movement of each of the armatures as a whole.

6. In an electrically controlled playing mechanism for pianos, a magnet rail, a series of armatures pivotally supported thereon, the free end of each armature having a pintle projecting from each side thereof, a series of hammer actuating elements controlled by said armatures and each being provided with a pair of spaced resilient ears having openings therein to engage said pintles, and adapted to be sprung into place 125 over the same.

7. In an electrically controlled playing mechanism for pianos, a magnet rail, a series of armatures pivotally supported thereon, the free end of each armature being pro- 130

vided with a pintle projecting from each side thereof, a series of hammer actuating elements controlled by said armatures, each of said hammer actuating elements having secured thereto a spring clip having spaced ears adapted to embrace the end of its respective armature, and being formed with openings to engage said pintles.

8. In an automatic playing mechanism for pianos, a rotating drum, friction shoes disposed in operative relation thereto, tapes extending from said friction shoes to the respective hammer actions, and means for adjustably securing said tapes to the shoes, such means comprising a clip secured to each shoe and having an opening through which said tape is adapted to pass, the metal from said opening being turned back upon the under side of said clip, and so arranged as to bite into said tape and hold it in position.

9. The combination with a piano having the usual hammer action, of an automatic playing mechanism therefor, means for supporting said playing mechanism, and means connected with the supporting means for adjusting said playing mechanism as a whole toward and from said hammer action, and also longitudinally thereof.

10. The combination with a piano having the usual hammer action, of an automatic rectilinearly adjustable means for supporting playing mechanism therefor, and universally rectilinearly adjusted means for supporting said playing mechanism in operative relation with said hammer action.

11. The combination with a piano, of automatic playing mechanism therefor comprising a supporting rail, a supporting bracket secured to the piano frame and carrying at its end an adjustable clamp, and a slideable connection between said clamp and supporting rail.

12. The combination with a piano, of automatic playing mechanism therefor comprising a supporting rail, and means for supporting said mechanism in the upper part of said case, such means comprising a bracket secured to the piano frame, a vertically adjustable clamp carried by said bracket, and longitudinally adjustable means connecting said clamp and rail.

13. An electrically controlled playing mechanism for pianos comprising a bar of magnetic material provided with pockets, electromagnet coils in said pockets, friction shoes governed by said magnet-coils and connected with the hammer actions, a rotary drum co-operatively associated with said friction shoes, a source of current for energizing said magnet coils, and a separate and independent power device for driving said rotary drum.

14. An electromagnetic playing mechanism comprising a rectangular bar of mag-

netic material having a line of pockets in its body and opening on one face of the bar, magnet coils and cores located within said pockets, armatures for said coils, said armatures being located upon the top face of said bar and overlying the open ends of the pockets, said armatures being hinged upon one face of the bar, actuating shoes connected to said armatures and lying normally adjacent to another face of the bar, said shoes having their toes underlying the bottom of the bar, and a movable power shaft underlying said shoes and supported from said bar.

15. An automatic musical instrument comprising a plurality of sound-producing elements, a hammer action therefor, an automatic electromagnetic playing mechanism comprising a bar of magnetic material extending lengthwise of the hammer action and having a line of pockets in its body and opening on one face thereof, magnet coils and cores located within said pockets and together with said bar constituting electromagnets, magnetically operated actuating mechanism for the hammer action, the elements of said magnetically operated actuating mechanism being grouped around said bar, and connections between the actuating mechanism and the hammer action.

16. An automatic musical instrument comprising a sound-producing element, a hammer action therefor, an electromagnetic playing mechanism comprising a rectangular bar of magnetic material extending lengthwise of the hammer action and having a pocket opening on one of its faces, a magnet coil and a magnet core extending into said pocket and together with said bar constituting an electromagnet, magnetically operated actuating mechanism for the hammer action, the elements of said magnetically operated actuating mechanism being grouped around and supported directly from said bar, and connections between the actuating mechanism and the hammer action.

17. An automatic musical instrument comprising a plurality of sound-producing elements, a hammer action therefor, and an electromagnetic playing mechanism comprising a rectangular bar of magnetic material having a line of pockets in its body, said pockets opening on one face of the bar, magnet coils and cores located within said pockets, armatures for said coils and cores, said armatures being located upon the top face of said bar and overlying the adjacent ends of said pockets, said armatures being hinged on one face of the bar, actuating shoes connected to the armatures and lying normally adjacent to another face of the bar, said shoes having their toes normally underlying the bottom of the bar, connections from the hammer action to the ac-

tuating shoes, and a movable power shaft supported upon said bar and underlying said shoes.

18. An automatic musical instrument comprising a plurality of sound-producing elements, a hammer action therefor, an electromagnetic playing mechanism connected with said hammer action, said mechanism comprising a single rail of magnetic material extending lengthwise of the hammer action and having a line of pockets, magnet coils and cores mounted within said pockets and by aid of said rail constituting electromagnets, an actuating mechanism the elements of which are grouped around said bar and controlled by said electromagnets, and connections between said actuating mechanism and said hammer action.

19. An automatic musical instrument comprising a plurality of sound-producing elements, a hammer action therefor, and an electromagnetic playing mechanism comprising a fixed rectangular bar of magnetic material, said bar having pockets opening upon one of its faces, magnet coils and cores mounted within said pockets, armatures for said coils and cores, said armatures being located adjacent to the top face of said bar and overlying the adjacent ends of said pockets, said armatures being hinged upon an adjacent face of said bar, actuating shoes connected to the armatures and lying normally adjacent to another face of said bar, said shoes having their toes normally underlying the bottom of the bar, connections from the hammer action to the actuating shoes, and a movable power shaft underlying said shoes and connected with said bar.

20. An automatic musical instrument comprising a plurality of sound-producing elements, a hammer action therefor, an electromagnetic playing mechanism comprising a fixed bar of magnetic material containing a plurality of chambers and supporting said mechanism, a magnet coil and core within each chamber, said cores being connected with said bar and together therewith and with the coils constituting electromagnets, actuating mechanism for the hammer action, said actuating mechanism being grouped immediately around said bar and including armatures coacting with said electromagnets, and connections between the actuating mechanism and the hammer action.

21. An automatic musical instrument comprising a plurality of sound-producing elements, a hammer action therefor, a casing for said elements and said action, an electromagnetic playing mechanism also located in said casing and comprising a rectangular bar of magnetic material containing a plurality of parallel chambers opening on one edge, a magnet coil and core within each chamber, an armature for each magnet, and movable actuating elements

for the hammer action, said magnet cores of said mechanism being connected directly with said bar and together therewith and with the coils constituting electromagnets, the several remaining elements of said mechanism being grouped around and supported from the several faces of said bar.

22. An automatic musical instrument comprising a plurality of sound-producing elements, a hammer action therefor, a casing for said elements and action, and an electromagnetic playing mechanism connected with said action and located in said casing, said playing mechanism comprising a fixed bar of magnetic material parallel to said hammer action, magnet coils and cores supported by said bar and together therewith constituting electromagnets, actuating mechanism for the hammer action, the elements of said actuating mechanism being grouped around and supported directly from said bar, and connections between the actuating mechanism and the hammer action.

23. A self-playing musical instrument comprising a plurality of sound-producing elements, a hammer action therefor, a casing for said elements and said action, and an electromagnetic playing mechanism connected with said hammer action and located within said casing, said mechanism comprising a rectangular supporting bar, said bar being provided with chambers extending directly into it, magnet coils and cores located wholly within said chambers and together with said bar constituting a plurality of electromagnets, armatures for said magnets, said armatures lying opposite the ends of said magnets on one face of said bar and each resiliently connected at one end of one side to said bar, actuating shoes pivotally mounted on the opposite ends of said armatures adjacent to another side of said bar, a rotating power shaft to be engaged by said shoes when the magnets are energized to attract the armatures and means for lessening the shock of engagement of said shoes with said shaft.

24. A self-playing musical instrument comprising a plurality of sound-producing elements, a hammer action therefor, a casing for said elements and action, and an electromagnetic playing mechanism connected with said hammer action and located within said casing, said mechanism comprising a rectangular supporting bar, magnet coils and cores carried in chambers formed in said bar and together therewith constituting a plurality of electromagnets, armatures for said magnets located adjacent to said coils and cores and in proximity to one face of said bar, said armatures being each resiliently supported on one face of said bar, actuating shoes each pivotally connected to an armature and located adjacent to another side of said bar, a rotating power-shaft to be

engaged by said shoes when the magnets are energized, and means upon the face of said bar adjacent to said shoes for lessening the shock of engagement of said shoes with said shaft.

25. In a self-playing musical instrument comprising a plurality of sound-producing elements, a hammer action therefor, a casting for said elements and said action, an electromagnetic playing mechanism connected with said hammer action and located within said casing, said mechanism comprising a supporting bar containing a plurality of chambers, a magnetic coil and core forming an electromagnet seated in each chamber and connected with said bar, armatures for said magnets disposed adjacent thereto, actuating shoes pivotally connected with said armatures and controllable thereby, adjustable yielding means forming a part of the connection between the shoes and the armatures, and a power shaft for operating said actuating shoes when moved into contact therewith.

26. An electromagnetic playing mechanism comprising a bar of magnetic material, magnet coils and cores forming electromagnets mounted in chambers in said bar, armatures movable relatively to said electromagnets, actuating shoes pivotally connected with said armatures and movable thereby, adjustable yielding means forming a part of the connection between said shoes and armatures, and a power shaft against which said actuating shoes may be moved by aid of said armature.

27. An electromagnetic playing mechanism comprising a rectangular bar of magnetic material provided with a plurality of chambers, an electromagnet carried in each chamber, the cores of said electromagnets being connected to said bar, armatures for said electromagnets on the top face of said bar, actuating mechanism including a plurality of actuating shoes, mechanism controlling said shoes, a power shaft, and means for regulating the travel of said actuating shoes toward said power shaft.

28. The combination of sound-producing elements, a hammer action for striking the same, a magnet rail made of a single bar of magnetic material provided with chambers, means for supporting said bar, electromagnets located within said chambers, armatures for said electromagnets, shoes pivotally connected to said armatures and disposed adjacent to said electromagnets in close proximity to said bar, means for actuating said shoes, flexible connections between said shoes and the hammer action, and means for taking up slack in said connections.

29. The combination of a hammer action, a magnet bar provided with a plurality of chambers spaced apart, an electromagnet contained within each chamber, the core of which is connected to the bar, an armature for each electromagnet resiliently mounted on the magnet bar, a shoe pivotally connected to each armature, means for actuating said shoes, a flexible connection between each shoe and the hammer action, and means for taking up slack in said connections.

30. An electrically controlled playing mechanism for pianos comprising a plurality of electro-magnetic members, a continuously rotating cylindrical member, a piano action including hammers, friction shoes each connected to a hammer to operate the same and each controlled by an electromagnet to cause said shoe to engage said rotating member and be actuated thereby and operate its connected hammer, an electric motor and a source of current therefor for driving said rotating member, and a source of current of low voltage and independent of the motor current for energizing the electromagnetic members.

In testimony whereof I have hereunto set my hand in presence of two subscribing witnesses.

IRVING B. SMITH.
